UNITED STATES PATENT OFFICE.

LOUIS MARCONI, OF NEW YORK, N. Y.

BOTTLE-CLOSURE.

1,130,183.

Specification of Letters Patent. Patented Mar. 2, 1915.

Application filed March 26, 1912. Serial No. 686,227.

To all whom it may concern:

Be it known that I, LOUIS MARCONI, a citizen of the United States, residing at New York, in the county of New York and State of New York, have invented new and useful Improvements in Bottle-Closures, of which the following is a specification.

This invention relates to bottle closures, and particularly to means for making bottles non-refillable, and has for its object to provide a device of simple construction adapted to be manufactured at a low cost and assembled with a minimum of labor.

It is an object to provide an efficient form of valve the closing of which will at all times be secure with a simple form of casing therefor and a means for retaining the valve in operative position which will at the same time protect the device from being tampered with by the insertion of instruments, wire, or the like.

A further object is to provide such a device which will occupy a minimum amount of space.

Other objects and advantages will be apparent from the following description and from the drawings, in which—

Figure 1 is an axial sectional view of a bottle neck equipped with my invention, Fig. 2 is a cross section on the line 2—2 of Fig. 1, Fig. 3 is a similar view on the line 3—3 of Fig. 1, Fig. 4 is a perspective of the retainer element.

There is illustrated a bottle neck 10, the outer portion of which is similar to the ordinary neck, the mouth 11 receiving a cork 12 wedged therein. The neck is slightly elongated, and is approximately cylindrical for the major portion of its length downward from the mouth, being slightly enlarged adjacent its base as at 12^a and formed with a conical seat 13 smaller at its lower end than the cylindrical part of the neck. The neck is joined to the body 14 of a bottle at the base of this seat, in the ordinary shape, or any which may be desired for the purposes of the user. Engaged in the neck there is a closure mechanism A, including the lower casing element 15, substantially in the form of an inverted cap of elongated tubular form, which may be formed integrally.

The casing element 15 is slightly enlarged or rabbeted as at 16 at its upper end and provided with an outwardly extending terminal flange 17. Engaged beneath the

flange and fitting the casing snugly there is a stopper 18 of cork, or other suitable material enlarged at its upper part, immediately beneath which a plurality of openings 19 are formed through the casing to allow a proper flow of fluid therethrough, as will be described. The enlarged portion 16 is threaded on its inner side and engaged therein is the outer element 20, which comprises the threaded annulus 21, having the lateral flange 22 at its upper edge smaller than, and adapted to lie parallel with, the flange 17, the two flanges coöperating to retain the leather washer 23, which is fitted snugly therebetween. The washer 23 projects beyond the periphery of the flange 17 and fits into the enlargement 12^a, whereby the mechanism A is retained in the neck. It will be observed that the flange 22 is of less diameter than the space within the cylindrical part of the neck 10. The threaded portion of the annulus is of such thickness that its inner surface lies flush with the inner surface of the casing 15, and is provided with inwardly projecting longitudinal lugs or ribs 24, adapted to serve as a check for the valve element 25, loosely reciprocable in the casing. The valve element is similar in form to the lower portion of the casing, and may be manufactured in the same way. It is provided with openings 19' adapted to register with those 19 in the casing when at the outer limit of its movement, where it is checked by the ribs 24. Its length beneath the openings 19' is such as to allow those openings to fall into the lower closed portion of the casing 15, so that its upper part closes the opening 19—when the device is in upright position.

Projected upwardly from the annulus 22 and conforming in transverse contour to the ribs 24 and forming a continuation thereof, there are legs 27 forming a cage supporting a protecting head 28 of cylindrical form, the body portion of which is of considerably less diameter than the passage through the neck and thus allows free passage of liquid therearound from the bottle. The transverse form of the legs and ribs mentioned is V-shaped, the intersection of the sides being presented inwardly, whereby a minimum retardance of the flow of liquid occurs. The head is provided with a series of four, more or less, spaced laterally projecting helicoidal flanges 29 abutting snugly

against the inner surface of the neck, but allowing free movement of the device into engaged position, as will be described. These flanges vary in their pitch slightly, 5 from the upper end—that is to say—they are inclined downwardly to a greater degree at their upper end than at their lower. Their lower ends are also slightly recurved upward forming checks 30. These devices 10 aim to prevent the introduction of wire beneath the head to engage and hold the valve in open position. Thus as viewed from the upper end it would appear that the flanges have a given pitch, but a wire bent to con- 15 form therewith would descend upon the upper side of the flanges owing to their lesser inclination at their lower parts, and would encounter the checks 30, preventing its further movement inward.

20 It will be noted that at the upper part of the enlargement 12^a an outwardly extending shoulder 12^b is formed, and the mechanism A assembled as described, is simply forced into the neck of the bottle until the washer 25 23 snaps beneath this shoulder, when it will be practically impossible to withdraw the mechanism, as the washer is then engaged between the flange 17 and the shoulder in such a way as to become wedged tightly 30 when withdrawal is attempted. If desired, of course, other means than the washer 23 may be utilized for the retention of the mechanism A in the neck, such as a cement 35 which may be incorporated in any suitable manner, or a resilient metal collar 23^a may be engaged between the casing 15 and the retainer, as shown in Fig. 4, the collar being provided with tongues 23^b adapted to snap beneath the shoulder 12^b. One method 40 of using cement would be to fill the enlargement 12^a with a cement paste slightly beyond the adjacent surface of the cylindrical portion 10 and extending down onto the conical seat a short distance. The washer 45 23 would be entirely omitted, but the mechanism as otherwise described, would be in-

roduced, and the cork 18 after engaging the seat below the cement, will press upon the cement, causing it to move inwardly over the flange 17 after it passes the shoulder 12^b, 50 and upon setting the mechanism will be held against removal. The retainer element is adapted to be cast integrally, though it may be formed in any manner found practicable, if desired. 55

It will be seen that the complete device is adapted to be produced at a low cost, and assembled and incorporated in a bottle with great facility.

What is claimed is:

In a device of the class described, a cylindrical bottle neck having an enlargement forming a shoulder and tapered at its lower part, a lower tubular casing having a peripheral flange at its upper end to fit snugly 60 in the neck, said casing open laterally a distance below the flange for communication with the interior of a bottle, a packing material around the casing for snug engagement upon said tapered part and with 65 the flange below the shoulder, and a guard element constructed for fixed engagement with the upper end of the casing and having a flange thereon smaller than the first named flange, an annular retaining member 70 between the flanges and extending into the said enlargement, the guard having a passage therethrough corresponding in size to that of the casing, also an extension below the last named flange engaged with the 75 lower casing, and a gravity valve operable within the lower casing, and constructed to be checked in decanting position by the guard element.

In testimony whereof I have hereunto set 80 my hand in presence of two subscribing witnesses.

LOUIS MARCONI.
